H E Perkinson

Attorney

UNITED STATES PATENT OFFICE.

H E PERKINSON, OF MEXIA, TEXAS.

MEANS FOR PRODUCING FLUID FLOW.

Application filed June 9, 1923. Serial No. 644,507.

To all whom it may concern:

Be it known that I, H E PERKINSON, a citizen of the United States, residing at Mexia, in the county of Limestone and State of Texas, have invented a new and useful Means for Producing Fluid Flow, of which the following is a specification.

This invention relates to a method and apparatus for creating and maintaining a flow of liquid from wells, particularly oil wells, by the use of heat.

An object of the invention resides in providing a device adapted for insertion into an oil well, containing a heated element adapted to be controlled for producing sufficient heat within the device for converting a portion of the liquid in the well into gas, and controlling the flow of the same, for utilizing it to create a flow of liquid in the device, and outwardly from the well through a suitable pipe connection therewith, it being understood that the well is otherwise sealed, during the operation of the device.

Another object of the invention resides in providing a device of the character above mentioned, wherein a pipe adapted for insertion into the well casing of an oil well or the like, has an enlarged section mounted on the lower end thereof, provided with a flared foot portion having suitable valves therein, said foot portion being adapted to seat on the bottom of the well, and the valved portions permitting a one-way flow through the foot portion to the interior of the enlarged section on the end of the pipe in which is mounted a heating device adapted for manual control to produce a desired degree of heat for creating a sufficient heat in the lower end of a well, to convert a portion of the liquid into a gas for control within the casing and pipe, in order to effect a flow of the liquid through the pipe and outwardly from the top of the well into a suitable container.

A further object of the invention resides in providing a method of producing a flow of liquid particularly adapted for oil wells, wherein heat is applied to the liquid at the bottom of the well within a restricted chamber having valve communication with the liquid in the well, to permit a one-way passage from the well to said chamber, subsequently controlling the gas generated from said liquid by the heating device in the cas-

ing for directing it in a suitable manner to produce a flow of the liquid upwardly and outwardly of the well, through a suitable pipe connection with said casing.

The invention also comprehends other objects and improvements in the details of construction, and arrangement of the parts, which are more particularly pointed out in the following description and claims directed to a preferred form of the invention, it being understood, however, that various changes may be made in the construction of the device for carrying out the purpose, which are within the scope and spirit of the invention as described and claimed.

In the drawing, forming a part of this application:

Figure 1 is a vertical sectional view, through the casing member carried by the lower end of a pipe inserted into an oil well, showing the construction of the casing for containing the heating element and controlling the flow of gas generated thereby, to create a liquid flow from the well through the pipe.

Figure 2 is an end view of the bell nipple or fitting connecting the pipe with the casing member.

Figure 3 is a view of the fitting carried by the casing member for receiving the bell nipple.

Figure 4 is a detail end view of the foot valve and packer, carried by the casing member.

Figure 5 is a detail view, on an enlarged scale, of the perforated tubing.

A pipe 1 is adapted to extend from the top of a well, downwardly into the casing and to the body portion of the well, where it carries a coupling sleeve 2, to which is secured the flowing device, indicated generally at 3, adapted to effect a flow of liquid through the pipe 1 and outwardly from the well.

The flowing device includes a bell nipple 4, the smaller end of which is screw threaded in the end of the coupling 2, while the larger end mounts a bushing member 5, of cylindrical form, which carries an enlarged cylindrical casing 6. The lower end of the casing 6 is provided with a foot member 7, which is threaded connected thereto, and which flares outwardly from the end of the casing 6, and is adapted to seat at the bottom of a well. This foot member is pro-

vided with a plurality of openings 8, for permitting a flow of liquid therethrough to the interior of the casing 6, which are governed by ball valves 9, mounted on the interior of the foot member, through the medium of suitable leaf holding springs 10, which normally tend to engage the valve 9, over the openings 8, which prevent a flow from the interior of the casing.

10 The bushing 5 is formed interiorly of the casing 6, with a depending sleeve extension 11, surrounding an opening through the bushing, and which is threaded interiorly for receiving a pipe section 12 of smaller diameter than the casing 6, and arranged in concentric relation therewith, which means houses a coiled electrical heating element 13, the lower end of the pipe section 12 receiving a cap 14 for closing the same in liquid tight relation. Above the end of the pipe section 12 in the bushing 5 is positioned a plug 15 threaded in the sleeve extension, and which forms an abutment, to limit the insertion of the pipe section 12 in the bushing. A threaded nipple 16 is seated in the plug 15, and secures the lower end of the fitting 17, carried by a wiring conduit 18 thereto, for receiving and holding the wires 19 from a source of energy, beyond the top 30 of the well, to the heating element 13.

The bushing 5 is provided with a plurality of openings 20 arranged in concentric relation beyond the depending sleeve projection 11, to permit a passage of fluid from the casing 6 through the bushing into the pipe 1.

40 The device constructed as above described, is adapted for insertion into a well, such as an oil well or the like, and is positioned in the well, with the flared open end of the foot member 7, seated on the bottom of said well, the pipe 1 extending to the top of the well and outwardly thereof to a suitable container for receiving liquid flowing from the well. The opening of the well around the pipe 1 is sealed, during the use of the invention, in order that the flowing of the liquid may be effected. Electric current is supplied to the coil 13 for heating the same, to a substantially high degree, which will instantly convert all liquid coming in contact therewith into gas, and produce a flow of the same upwardly through the opening 20 and up into the pipe 1, which will create a suction at the foot member 7, so that liquid will be drawn inwardly through the openings 8, into the bottom portion of the casing, and the creation of gas by the heating element is sufficiently fast that the suction created will cause a considerable quantity of liquid to be struck into the casing, at the lower end, so that the rising gas will push upwardly through the opening 20 on said liquid and force the same outwardly 60 through the pipe 1, into the receptacle at

the top of the well. It will be seen that in this way, both liquid and the gas generated by the heating coil 13 will be caused to flow upwardly and outwardly from the pipe 1 into the receptacle, which will produce a 70 continuous flow of liquid from the well, as long as said heating element is energized.

While this device has been described for use in connection with wells, and particularly oil wells with which it is especially 75 adapted and designed for use, it is to be understood that it may be used for circulating any liquid medium in the same manner.

It is to be noted, however, that it has particular advantages in connection with its use in oil wells, for the reason that it prevents the formation of paraffin and like surfaces, which clog the pores of the oil bearing rocks.

What is claimed is:

1. A device for circulating fluid comprising a casing, a foot member mounted on the casing having an opening at the bottom thereof, and one-way valve passages in the sides thereof, a bushing fitting on the upper end of the casing having a restricted passage therein, a housed heating element carried by said bushing and extending within the casing, and a conducting point connected with said bushing for conveying fluid 90 circulated by the heating thereof in the casing by said heating element.

2. A device for circulating fluid comprising a casing, a foot member adapted to seat on the bottom of the well and formed to admit fluid from the outside to the inside thereof, a bushing mounted on the upper end of the casing, a pipe connected to said bushing for conducting fluid from the casing and for supporting the casing in the bottom of the well, and a heating element suspended from the bushing in the casing and spaced from the inner walls of said casing.

3. A device of the class described comprising a pipe for extension into an oil well, a bushing mounted on the lower end of said pipe having arcuate passages formed therein, a casing suspended from the bushing, a foot member mounted on the casing having an open flared lower end adapted to seat at the bottom of the well, said foot member being formed with passages to permit a flow of fluid into said member, a housing suspended from the bushing in concentric relation to the casing and closed at the lower end, and a heating element mounted in the housing.

4. A device of the class described comprising a pipe for extension into an oil well, a bushing mounted on the lower end of said pipe having circumferentially arranged passages therethrough, a casing suspended from the bushing, a foot member mounted on the lower end of the casing, having a 120

lower flared end portion adapted to seat at the bottom of the well, said foot member being formed with a valved one-way passages to permit entrance of fluid from the exterior thereof to the interior of the member and the casing, the circumferentially arranged passages in said bushing forming a restricted passage for fluid from the casing into the pipe, the housing suspended 10 from the bushing within the casing, and arranged concentrically thereto, and electri-

cal heating means mounted in said housing.

In testimony whereof I have signed my name to this specification, this the 22nd 15 day of May, A. D. 1923, at Mexia, Limestone County, Texas, in the presence of two subscribing witnesses.

H E PERKINSON.
